UNITED STATES PATENT OFFICE.

HOMER J. HOYT, OF DETROIT, MICHIGAN, ASSIGNOR TO MORGAN & WRIGHT, A CORPORATION OF MICHIGAN.

MOLD-ALINING DEVICE.

1,256,693.

Specification of Letters Patent.

Patented Feb. 19, 1918.

Application filed November 15, 1916. Serial No. 131,390.

To all whom it may concern:

Be it known that I, HOMER J. HOYT, a citizen of the United States, residing at Detroit, county of Wayne, and State of Michigan, have invented certain new and useful Improvements in Mold-Alining Devices, of which the following is a full, clear, and exact description.

This invention relates to mold-alining devices and with respect to its more specific features to an alining device employed for centering molds in a vulcanizing press-chamber.

The principal object of the invention is to provide a device of the kind described which shall guide a mold to alined position and having placed it in such position shall prevent further motion out of alinement. Another object of the invention is to provide a device of the kind mentioned which may be adjusted so that molds of various sizes may be alined and held in position with equal precision.

In the accompanying drawings in which 25 one of the various possible embodiments of the invention is shown;

Figure 1 represents a sectional plan view of a vulcanizing press embodying my invention, the section being taken on line 1--1, 30 of Fig. 2;

Fig. 2 represents a partial sectional elevation of the apparatus shown in Fig. 1; and

Fig. 3 is an enlarged detail view of an 35 alining member and the means for securing it to the side of the press-chamber.

Referring now to the drawings there is shown the usual type of vulcanizing heater-press comprising a substantially cylindrical 40 press-chamber 1, mounted about which are guides 2 supporting a top 3 adapted to be moved downwardly into closing position upon the top of the chamber. Mounted in the interior of the press-chamber is a hydraulically operated platen 4 adapted to support molds 5 which are delivered from a device 6 adapted to unload the molds from a conveyer belt (not shown). Projecting from the inside of the chamber are three 45 narrow upright brackets 7 here shown as equi-distantly spaced and projecting a sufficient distance into the chamber to contact with the sides of molds 5 to serve as alining members therefor. The lower portion 55 of each bracket is retained by a U-shaped

support 8 which is bolted to the interior of the chamber 1. The upper portion of each bracket is provided with a hole which when the bracket is positioned is adapted to be brought into alinement with apertures in spaced blocks 9 which are also secured to the interior of the chamber. A removable bolt 10 passes through the apertures in the bracket and blocks and thereby secures the bracket in position. By removing this bolt 60 65 the bracket may be slipped from its supports and removed from the chamber. The upper portion of each bracket is provided with an inclined portion 11 which joins the straight portion 12, which latter is adapted to contact with the sides of the mold for substantially its entire depth when the latter is in position. The platen 4 is notched to permit the brackets to pass therethrough.

In operation the molds are delivered by 70 the unloader 6 to the press and travel by their momentum across the mouth thereof until they contact with the three brackets along whose inclined faces they move until they come to rest upon the floor of the platen 80 or upon the preceding mold, with their sides in contact with the faces of the brackets. When one mold is positioned the platen is lowered in the usual manner to permit the reception of another mold which is similarly alined and so on until the chamber is 85 filled.

It will be observed according to the construction outlined that the brackets 7 not only guide molds to alined position but hold 90 them in that position until the platen is moved for the reception of the next mold. Further, brackets projecting various distances into the chamber may be employed thereby permitting alinement of molds of 95 any given size, and it will be observed that since the brackets contact with the sides of the molds along substantially tangential lines only, that molds of various sizes may be alined with equal precision.

Having thus described my invention what I claim and desire to protect by Letters Patent is:—

1. In an apparatus of the kind described, in combination, a chamber adapted to receive molds, a plurality of brackets spaced apart and secured to the side wall of said chamber and adapted to engage the molds to aline them when received in the chamber, and a mold supporting platen having a plu- 105 110

rality of recesses formed to receive said brackets.

2. In a vulcanizing press a head, a shell, said head and shell being adapted for relative movement to provide an open space therebetween for charging the press with molds, a platen for supporting a column of molds, a table exterior to and inclined toward said vulcanizer for supporting the molds being fed thereto and having its lower edge at approximately the height of the mouth of said shell when in charging position, and a plurality of devices for centering the molds in said shell, said devices being secured at fixed positions to the interior of the shell at its upper edge and below its mouth to permit uninterrupted passage of the molds into said mouth, said devices extending down the wall of said shell to approximately a distance equal to the height of a mold.

3. In a vulcanizing press a head, a shell,

said head and shell being adapted for relative movement to provide an open space therebetween for charging the press with 25 molds, a platen for supporting a column of molds, a table exterior to and inclined toward said vulcanizer for supporting the molds being fed thereto and having its lower edge at approximately the height of the 30 mouth of said shell when in charging position, and a plurality of devices for centering the molds in said shell, said devices being detachably secured at fixed positions to the interior of the shell at its upper edge 35 and below its mouth to permit uninterrupted passage of the molds into said mouth, said devices extending down the wall of said shell to approximately a distance equal to the height of a mold. 40

Signed at Detroit, Michigan, this 6th day of November, 1916.

HOMER J. HOYT.
